FRED J. HEIDEMAN, OF DETROIT, MICHIGAN, ASSIGNOR, BY DIRECT AND MESNE ASSIGNMENTS, TO HOUSEHOLD UTILITIES CORPORATION, OF DETROIT, MICHIGAN, A CORPORATION OF DELAWARE.

CONTROL-VALVE FOR COMPRESSORS.

1,356,205.

Specification of Letters Patent. Patented Oct. 19, 1920.

Application filed October 13, 1919. Serial No. 330,413.

To all whom it may concern:

Be it known that I, FRED J. HEIDEMAN, a citizen of the United States, residing at Detroit, in the county of Wayne and State of Michigan, have invented a new and useful Control-Valve for Compressors, of which the following is a specification.

This invention relates to gas compressors and more particularly to control valves for the discharge port of such compressors.

It is the object of the invention to provide a valve construction for gas compressors adapted for venting a normal charge of compressed gas, and having a supplementary provision for establishing a larger vent, when a liquid has accumulated in the cylinder or cylinders of the compressor, due to condensation of the gas.

In attaining this object the invention contemplates the employment of a discharge valve acted upon by two springs differing in strength, the weaker spring yielding to permit venting of a gas under normal conditions, and the stronger spring yielding, when said gas has liquefied, to increase the vent opening, as is required by the relatively great inertia of the liquid.

A preferred embodiment of the invention is described in the following specification and illustrated in the accompanying drawing, wherein,

Figure 1 is a sectional elevation of a gas compressor improved in accordance with the invention.

Fig. 2 is a fragmentary duplication of a portion of Fig. 1 drawn to a relatively large scale, said portion disclosing one of the discharge valves.

Fig. 3 is a sectional view of a member forming a mounting for the discharge valve, taken on line 3-3 of Fig. 2.

Figs. 4 and 5 are views respectively of a discharge valve, and a member which forms a stop limiting the normal opening of the valve and an abutment for opposite ends of the two springs, whereby the valve is held seated.

In these views the reference character 1 designates the cylinders and 2 the pistons of a gas compressor, the cylinders being formed *en bloc* and having the detachable head 3, held in place by bolts 4. Between the cylinders and said head there is clamped a plate 5, which forms a closure for the dis-

charge ends of the cylinders, chambers 6 being formed in the head 3 adjacent said plate, and respectively in registration with the cylinders. In each of said chambers there is disposed a seat-forming member 7 for a spring abutment 8 and a discharge valve 9, said member 7 being held stationary by an integral shank 10 having screw-threaded engagement with the plate 5. Normally the spring abutment 8 (of each cylinder) is stationary, and venting of the cylinder is effected by the valve 9. The latter controls a port 11 in the shank 10 and has an upstanding stem 12 which telescopes within a stem 13 depending from the spring abutment 8. The lower end of the stem 13 acts as a stop to limit the opening movement to which the valve 9 is subjected under normal conditions, and the opening movement which the spring abutment 8 undergoes under abnormal conditions is limited by lugs 14 integral with the head 3. A coiled spring 15 urges the spring abutment 8 to its seat upon the upper portion of the member 7, and a relatively weak coiled spring 16, interposed between the two valves, urges the valve 9 to its seat. Ports 17 opening laterally in the member 7 afford an escape from said member into the chamber 6 for such gas as normally vents through the port 11. When an accumulation of condensed gas in the cylinder necessitates an increased vent capacity, the abnormal pressure will effect an unseating of both the member 8 and valve 9, the latter pushing up the former, and the liquid escaping into the chamber 6 through the ports 17. The two side chambers 6 open into the control chamber as indicated at 18, and a discharge passage 19 leads from said central chamber.

The described construction has an especial application to refrigerating apparatus which is automatically temperature controlled, so that there is a tendency for the refrigerating medium to condense in the cylinders of the compressor during the periods when the apparatus is idle.

What I claim is:

1. In a gas compressor, the combination with a valve controlling a discharge port of said compressor, of a spring seating said valve designed to yield under a normal gaseous pressure, a member forming a mov-

- able abutment for said spring and forming a stop limiting the opening movement of the valve under normal gaseous pressure, a relatively strong spring normally resisting movement of said abutment member, yieldable under an abnormal pressure upon the valve to increase the opening movement thereof, and means limiting the movement of said abutment member.
- 10 2. In a gas compressor, the combination with a member ported to form an outlet from said compressor, of a valve seated upon said ported member and controlling said outlet, a spring housed within said ported member, seating said valve and designed to yield under a predetermined gaseous pressure, a movable abutment for said spring seated upon said ported member, telescoping stems upon said valve and abutment member limiting the normal opening movement of the valve, and a relatively strong spring resisting movement of said abutment and yieldable under an abnormal

pressure on the valve to permit an increased opening thereof.

25

3. In a gas compressor, the combination with a cylinder casing and a detachable head therefor, of a plate clamped between said casing and head, the latter being formed with chambers registering with the respective cylinders adjacent said plate, members respectively secured to said plate within said chambers formed with outlets for the cylinders, valves seated upon said members controlling said outlets, springs seating said valves yieldable under predetermined normal pressures within the cylinders, and stronger springs limiting the normal opening movement of the valves yieldable to permit an increase of said movement upon a predetermined abnormal pressure within the cylinders.
